UNITED STATES PATENT OFFICE.

GEORGE C. BEIDLER, OF ROCHESTER, NEW YORK.

PHOTOGRAPHING APPARATUS.

1,155,785.

Specification of Letters Patent.

Patented Oct. 5, 1915.

Application filed November 2, 1911. Serial No. 658,178.

To all whom it may concern:

Be it known that I, GEORGE C. BEIDLER, a citizen of the United States of America, and resident of Rochester, in the county of Monroe and State of New York, have invented certain new and useful Improvements in Photographing Apparatus, of which the following is a specification.

This invention relates to photographing and developing apparatus and particularly to means for immersing photographic films in a liquid which is provided for acting on the coated surfaces of the films.

An object of this invention is to provide novel means for immersing a film after it has been delivered to a receptacle, the present embodiment of the invention being associated with a receptacle designed to contain hypo or fixing fluid. It is to be understood however that the receptacle with which the immersing device is associated may contain any liquid adapted to act on the coated surface of the film or it may be water used to rinse or wash the film.

A further object of the present invention is to provide means for elevating and releasing the immersing frame, novel means being provided for controlling the descent of the said frame within the receptacle, the said controlling means allowing a gradual descent of the said immersing frame in the receptacle. It has been found in practice that where an immersing frame is elevated and then released and allowed to descend by gravity, unrestricted, the said frame splashes the liquid in the receptacle to such an extent as to be objectionable and therefore the present invention is directed to control the descent of the said frame, the same being associated with and connected to the frame or operating mechanism thereof.

With the foregoing and other objects in view, the invention consists in the details of construction and in the arrangement and combination of parts to be hereinafter more fully set forth and claimed.

In describing the invention in detail, reference will be had to the accompanying drawings forming part of this specification

wherein like characters denote corresponding parts in the several views, and in which—

Figure 1 illustrates a view in side elevation of a photographing and developing apparatus with the power applying element omitted in order to more fully show the immersing frame and its operating mechanism; Fig. 2 illustrates a perspective view of a fragment of the casing of the photographing and developing apparatus with a fragment of the immersing apparatus applied; Fig. 3 illustrates a sectional view taken approximately centrally of Fig. 2 of a fragment of the casing with the immersing device in longitudinal section; Fig. 4 illustrates a sectional view of a pneumatic cushion utilized in connection with the immersing frame; Fig. 5 illustrates an enlarged detail view in section of a fragment of the piston rod of the cushioning device more fully showing the control of a port for regulating the action of the cushioning device; Fig. 6 illustrates a perspective view of a combined link arm and finger; and Fig. 7 illustrates a sectional view of the bracket and a bearing thereon associated with parts of the apparatus. Fig. 8 illustrates the details of mechanism for operating the immersing frame.

In these drawings 10 denotes a casing of a photographing and developing apparatus, provided with a camera 11 and other elements necessary to the formation of a photographing and developing apparatus which will not be described in detail. It is sufficient, it is believed, for a disclosure of the present invention to state that films are exposed to the action of light and are carried through the casing 10 and delivered to the receptacle 12 which is adapted to contain fluid which will act on the coated surface of the film. As the apparatus is now used, the said receptacle 12 contains hypo or fixing fluid and the film, after being developed and delivered to the receptacle 12 is subjected to the action of said fixing fluid. Difficulty has been experienced in delivering film in its wet state after being developed,

to the fixing solution, yet maintaining the said film in an uncrumpled, unfolded, or uncreased state to the liquid within the receptacle 12. To overcome the difficulties just stated provision has been made for spreading the film over the surface of the liquid within the receptacle 12 prior to its being released therein. To accomplish the result just indicated, that is to say, of spreading the film, spreading fingers 13 have been mounted in brackets 14 so as to be oscillatable with relation to the receptacle 12, the said fingers 13 being operated by the arm 15 which is actuated from the gear wheel 16 in any appropriate way.

The gear wheel 16 is driven by the pinion A, which pinion is rotated in any suitable manner and the gear wheel 16 has a cam 17 on its face engaged by the lug 18 on the arm 19 so that as the cam 17 is rotated, the arm 19 ascends and descends under the control of the cam. The arm 19 has pivotally connected to it, the links 20 and 20^a which links are mounted on shafts 21 journaled in the brackets 22 which have their bases 23 anchored to the casing 10. While I have referred to the brackets 22 in the plural, it is to be understood that a duplicate of the bracket shown in Fig. 1 is provided on the opposite side of the receptacle 12 and a view thereof is prevented by the intervention of the elements appearing in elevation in Fig. 1.

The shafts 21 are carried by the cranks 24 which shafts oscillate in bearings 24^a formed integral with the brackets 22. The cranks 24 are connected to lugs 25 of the immersing frame 26 so that as the arms of the cranks 24 oscillate, the frame 26 ascends and descends with relation to the receptacle 12 and as they descend within the receptacle 12, a film which has been spread in the receptacle and is supported by the liquid contents thereof is immersed in the said liquid contents by a downward and longitudinal movement of the frame. The movement thus given the frame and the film results in dislodging air bubbles from the under surface of the film and allows access of the liquid contents of the receptacle to the treated surface of the film.

In order to prevent splashing of the liquid contents of the receptacle by the too rapid descent of the frame, one of the links 20^a has an arm 27 to which there is pivotally connected a hollow piston rod 28, the said hollow piston rod extending into the head 29 of a cylinder 30. The hollow piston rod extends through a piston 31 within the cylinder and upon inward movement of the piston within the cylinder, air compressed by the cylinder escapes through the hollow piston rod and through a port 31' which is provided in the said piston rod. In order to control the escape of air through the piston rod, the port is guarded by a screw 32

having a tapered side 33 in order that the port opening may be increased or diminished according to the adjustment of the screw 32. It is apparent from an inspection of Fig. 5 that the port opening will be diminished as the screw descends into the port and vice versa. In order to permit a slight oscillation of the cylinder to accommodate the movement of the arm 27, the said cylinder has an arm 34 hinged to a plate 35 which is secured to the casing 10, so that as the arm 27 oscillates, the cylinder may be likewise oscillated.

The combined link 20^a and arm 27 has an integral finger 36 extending rearwardly within reach of an operator in order that the frame may be manually operated or elevated out of the receptacle when the film is to be inspected or for other purposes.

From what has been stated and by reference to the drawing, it will, it is thought, be observed that the gear wheel 16, operating as it does, communicates motion to the cam 17 and operates the arm 19 which actuates the immersing frame. The gear wheel 16 is further provided with a side cam B which actuates the arm 15, which arm actuates the mechanism to which the spreading fingers are operatively connected, the relation being such that the recess in the cam 17 is in position to allow the arm 19 to descend, thus permitting the descent of the immersing frame at a time when the widest part of the cam B is engaged by the arm 15 for holding the spreader fingers approximately parallel with the arm 19 or in their open position, to which position they have traveled to spread the film in the receptacle 12, so that when the immersing frame descends in the receptacle 12, it may carry the spread film into the liquid contained therein. Just prior to the elevation of the arm 19 by the cam 17, the arm 15 is released by the cam B and the spreading fingers are moved inwardly under the influence of the actuating mechanism provided for said fingers.

While I have, in the present application, described and shown an immersing frame and means for spreading film over the surface of the liquid within the receptacle, and have furthermore shown means for operating the immersed frame, also means for operating the film spreading means from a driven shaft, the claims in the present application are not directed to those features, but those features constitute part of the subjects matter of other applications for patent filed by me, one of said applications having been filed January 3, 1910, and numbered 535,939, and another of said applications bearing date of May 20, 1911, and Serial No. 628,415.

I claim—

1. In a photographing apparatus, a receptacle adapted to receive film after its ex-

- posure to light, the said receptacle being adapted to contain a fluid, a frame for immersing film in the fluid, and mechanically operated means for controlling the movement of the frame. 5
2. In a photographing apparatus, a receptacle adapted to receive film after its exposure to light, the said receptacle being adapted to contain a fluid, means for immersing film in the fluid, and mechanically operated means for limiting the movement of the said means for immersing the film. 10
3. In a photographing apparatus, a receptacle adapted to receive film after it is exposed to light, the said receptacle being adapted to contain a fluid, a frame for immersing the film in the fluid, and a member connected to the frame, associated with means for causing an up and down movement of the frame. 15
4. In a photographing apparatus, a liquid container to which film is delivered, an immersing frame, means for supporting the frame, means for operating the supporting means to move the frame with relation to the container, and means for limiting the movement of the frame in one direction. 20
5. In a photographing apparatus, a liquid container to which film is delivered, an immersing frame, means for supporting the frame, means for operating the frame supporting means to raise the frame, said frame supporting means being released to permit the frame to descend by gravity, and means for controlling the descent of the frame. 25
6. In a photographing apparatus, a liquid container to which film is delivered, an immersing frame, means for supporting the frame, means for operating the frame supporting means to raise the frame, said frame supporting means being released to permit the frame to descend by gravity, and means for controlling the descent of the frame comprising a cushion operative on the descent of the frame. 30
7. In a photographing apparatus, a container for liquid, an immersing frame, means for supporting the immersing frame above the container, means for operating the supporting means whereby the frame is elevated, said supporting means being released whereby the frame may descend by gravity, a cushioning device, and means for connecting the cushioning device to the frame. 35
8. In a photographing apparatus, a container for liquid, an immersing frame, means for supporting the immersing frame above the container, means for operating the supporting means whereby the frame is elevated, said last mentioned means having provision for permitting the supporting means to drop whereby the frame may descend by gravity, a cushioning device comprising a cylinder, means for oscillatingly supporting the cylinder, a hollow piston rod 40
- movable in the cylinder, a piston in the cylinder through which the piston rod extends, said piston rod having a port, means for controlling the port, and means for connecting the piston rod to the frame. 45
9. In an apparatus relating to photography having a receptacle for containing fluid, means for immersing film in the fluid, means for supporting the means for immersing the film, means for operating the means for supporting the film, immersing means to raise and lower the said means for immersing the film, and means for controlling the descent of the film immersing means. 50
10. In an apparatus relating to photography having means for containing liquid to which film is delivered, an immersing frame, means for moving the film into and out of the liquid, and means for controlling the last mentioned means to regulate the movement of the immersing frame. 55
11. In an apparatus relating to photography having means for containing liquid to which the film is delivered, an immersing means, means for moving the immersing means into and out of the liquid, and means for controlling the last mentioned means to control the movement of the immersing means. 60
12. In an apparatus relating to photography having a receptacle for containing fluid and for receiving film, a frame, means for movably supporting the frame to allow travel of said frame vertically and longitudinally in the receptacle, means for elevating the frame and for releasing the frame to permit the descent of said frame in the said receptacle by gravity, and means for controlling the descent of the frame. 65
13. In an apparatus relating to photography having a receptacle for containing fluid and for receiving film, a frame, means for movably supporting the frame to allow travel of said frame vertically and longitudinally in the receptacle, means for elevating the frame and for releasing the frame to permit the descent of the said frame in the said receptacle by gravity, means for controlling the descent of the frame comprising a cushion having means for connecting the said cushion to the frame, and means for regulating the cushion. 70
14. In an apparatus relating to photography having a receptacle for containing fluid and for receiving film, a frame, cranks oscillatingly mounted in operative relation to the receptacle, means for connecting the cranks to the frame, means for oscillating the cranks, an arm connected to one of the cranks, and a cushioning device connected to said arm. 75
15. In an apparatus relating to photography having a receptacle for containing fluid and for receiving film, a frame, cranks 80

oscillatingly mounted in operative relation to the receptacle, means for connecting the cranks to the frame, means for oscillating the cranks, an arm connected to one of the cranks, a hollow piston rod pivotally connected to the arm, said piston rod having a port, means for controlling the port, a cylinder and a piston in the cylinder through

which the piston rod extends and to which said piston rod is connected.

In testimony whereof, I affix my signature in the presence of two witnesses.
